UNITED STATES PATENT OFFICE.

ADOLPH L. GOLDSCHMIDT, OF NEW YORK, N. Y.

MEANS FOR CONNECTING CIRCUIT-WIRES TO ELECTRIC MOTORS.

No. 918,844.

Specification of Letters Patent.

Patented April 20, 1909.

Application filed August 30, 1908. Serial No. 882,539.

To all whom it may concern:

Be it known that I, ADOLPH L. GOLDSCHMIDT, a citizen of the United States, residing at the city of New York, in the county 5 of New York and State of New York, have invented certain new and useful Improvements in Means for Connecting Circuit-Wires to Electric Motors, of which the following is a full, clear, and exact description.

10 In connecting up the circuit wires with motors and other electrical devices, it is a common practice to cut away or terminate the conduit for the wires at a point adjacent to the ceiling of the room, and then lead the 15 wires downwardly beyond the end of the conduit to the binding posts or terminals on the motor. In so doing, the wires are left exposed throughout a considerable length, and are not only in the way, but are also liable to 20 have the insulation stripped therefrom by objects striking against them, and to be disconnected from the binding posts of the motor from the blows and strains to which they are subjected. This is extremely objectionable, not only on account of the danger, but 25 on account of the trouble and inconvenience caused.

The purpose of my invention is to provide 30 means whereby the circuit wires may be completely covered and protected down to their points of connection with the terminals of the motor, and in such a way that any 35 blows or strains to which said wires might otherwise be subjected cannot be transmitted to the terminals with the result of disconnecting the wires therefrom.

It is also a purpose of my invention to provide, in connection with the means for completely covering and protecting the circuit 40 wires, means for shielding and protecting the binding posts on the motor.

In carrying out my invention, I extend the conduit down to a point adjacent to the circuit terminals on the motor and firmly secure 45 the same at its free end to the motor casing.

The details of the invention will hereinafter appear and that which I regard as new will be set forth in the claim.

In the drawings forming part of this specification, Figure 1 is a partial end view of an electric motor, showing the application of my invention thereto; Fig. 2 is a similar view, showing the securing bracket for the conduit in raised position, in section; Fig. 3 is a detail sectional view of the lower end of the con-

duit, and Fig. 4 is a detail view showing a modification of the invention.

Like reference numerals indicate like parts in the different views.

The casing 1 of the motor is provided with 60 the binding posts 2, which, as usual, are mounted upon an insulating base or block 3. The conduit 4 through which the circuit wires pass is provided with a downwardly extending leg or member 5 which extends 65 down to a point adjacent to the binding posts 2, the lower end thereof terminating a short distance above said binding posts.

6 is a shield which is secured to the lower end of the vertical conduit member 5 and is 70 itself secured to the casing 1 of the motor. In the form of my invention shown in Figs. 1 and 2 of the drawing, the shield 6 constitutes a housing for the binding posts 2, the same when in place completely inclosing said 75 binding posts. The upper end of said shield or housing is provided with a contractible sleeve or collar 7 through which the conduit member 5 passes, the said collar, with the bolt 8 which extends through lateral ears 80 thereon, constituting a clamp by means of which said shield is secured to said conduit member. The lower end of said shield is provided with flanges 9 through which screws or other attaching means may be 85 passed for securing the shield to the motor casing.

The lower end of the conduit member 5 has been shown as screw-threaded and provided with a bushing 10 having a central 90 opening 11 therein slightly smaller in diameter than the diameter of the passage through the conduit member 5. The walls of the opening 11 are rounded, as shown, the purpose of the said bushing being to protect the 95 wires passing through the conduit from the bur 12 which is formed at the end of the conduit section.

In using my improved device the circuit 100 wires 13 are extended down through the conduit member 5 and the insulation removed from those portions thereof which project beyond the end of said conduit member. The shield 6 is raised to the position in which it is shown in Fig. 2 of the drawing, thus 105 uncovering the binding posts 2 and the projecting ends of the wires 13 and permitting of the ready connection of said wires with said binding posts. When these connections have been made, the shield 6 is moved down- 110

wardly to the position shown in Fig. 1 of the drawing and screwed to the motor casing, as shown. The nut on the bolt 8 is then screwed up and the conduit member 5 is locked to the shield 6, and through said shield to the motor casing 1. The circuit wires are then completely inclosed by the conduit member 5 in the room in which the motor is located, and are also completely protected against blows and strains which would tend to remove the insulation from said wires and to separate or disconnect said wires from the binding posts 2. No movement whatever of said wires is permitted independent of the motor and of the conduit through which the wires pass. At the same time the binding posts 2 are completely protected by the shield 6.

While my invention has been illustrated and described as specially intended for use in connection with an electric motor, it will be obvious that it is not limited to this particular use. Where the terms "motor" and "motor casing" are used in the following claim, therefore, it will be understood that they comprehend in the one case any other electrical device which has circuit terminals

used for external wires, and in the other any other fixed support.

Having described my invention, I claim:—

In combination with a wall or ceiling, a fixed electrical translating device, a conduit pipe fastened at one end to said wall or ceiling and extending at its other end into proximity, but not into engagement with, said device, electrical conductors extending from said device through said conduit pipe, and a shield coöperating with said pipe and said device to completely inclose said conductors adjacent to said device, said shield being secured to said conduit pipe and to said device to constitute the sole medium of resistance against all strains therebetween and preclude swaying or independent movement of the conduit pipe, whereby the conductors can be exposed for connection and are normally protected against damage.

In witness whereof, I subscribe my signature, in the presence of two witnesses.

ADOLPH L. GOLDSCHMIDT.
